UNITED STATES PATENT OFFICE.

WILLIAM H. FERGUSON, OF DENVER, COLORADO, ASSIGNOR OF ONE-HALF
TO JOHN A. FERGUSON, OF DENVER, COLORADO.

COMBINED CURB AND GUTTER.

SPECIFICATION forming part of Letters Patent No. 728,693, dated May 19, 1903.

Application filed January 8, 1903. Serial No. 138,301. (No model.)

To all whom it may concern:

Be it known that I, WILLIAM H. FERGUSON, a citizen of the United States, residing at Denver, in the county of Denver and State of Colorado, have invented new and useful Improvements in a Combined Curb and Gutter, of which the following is a specification.

My invention relates to street-curbings; and it consists in the combined curb and gutter and the combined curb and gutter block herein-after described, and particularly pointed out in the claims appended.

In the accompanying drawings, Figure 1 is a transverse section of my improved combined curb and gutter, taken in the plane indicated by the line 1 1 of Fig. 2; Fig. 2, a plan of the same, and Fig. 3 a perspective view of one of the blocks of which the combined curb and gutter is formed.

Similar letters of reference designate corresponding parts in all of the views of the drawings, referring to which—

A is a street; B, a sidewalk of bricks or other suitable material *a*, laid on earth, concrete, or other suitable material *b*, and C my improved combined curb and gutter. The latter is formed of blocks D of concrete, burnt clay, or other suitable material laid end to end in a bed of cement or the like and joined

by cement or other suitable means. The blocks D are similar in construction, and therefore a detailed description of the one shown in Fig. 3 will suffice to impart an understanding of all. Said block, which may be molded or formed in any other suitable manner, comprises a horizontal portion *c*, designed to rest flush with the surface of the street A, Fig. 1, and a vertical portion *d* of greater thickness than the horizontal portion, said vertical portion being designed to rest flush with the surface of the pavement B and having one or a plurality of cavities *e* in its side adjacent to the same for a purpose presently described. When desired, an angular metallic reinforcement E, preferably an angular fluted plate, may be embedded in the block, Figs. 1 and 3, with a view of strengthening the joint between the horizontal portion *c* and the vertical portion *d*. I desire it distinctly understood, how-

ever, that the block may be made without the

said reinforcement without involving a departure from the scope of my invention.

In laying my improved curb and gutter the blocks D are arranged end to end in the bed of cement in such position that the upper 55 sides of the portions *c* are flush with the surface of the street A, after which the earth, concrete, or other material *b* is rammed into the cavities *e* and the surface *a* of the sidewalk is made flush with the upper side of the 60 portions *d*.

It will be observed that in virtue of the earth or other material *b* below the surface of the sidewalk being rammed into the cavities *e* of the blocks D the said blocks will be held 65 to the sidewalk and at the same time their vertical portions *d* will be supported and enabled to withstand the blows to which curbs are ordinarily subjected. It will also be observed that the cavities *e* in the vertical portions *d* of the blocks are advantageous because of the saving in the material of which the blocks are formed and also because they render the blocks light, and consequently lessen the cost of shipping the blocks from 75 place to place.

Having described my invention, what I claim, and desire to secure by Letters Patent, is—

1. As an improved article of manufacture, 80 a combined curb and gutter block comprising a horizontal portion, and a vertical portion, integral with the horizontal portion, and having one or more cavities *e* in its vertical side remote from the horizontal portion; said cav- 85 ity or cavities being open at but one side.

2. As an improved article of manufacture, 90 a combined curb and gutter block formed of concrete or other suitable material and comprising integral horizontal and vertical portions; the vertical portion being of a greater thickness than the horizontal portion, and having one or more cavities in its vertical side remote from the horizontal portion, and an angular, metallic reinforcement embedded in 95 the horizontal and vertical portions.

3. As an improved article of manufacture, 100 a combined curb and gutter block formed of concrete or other suitable material and comprising integral horizontal and vertical por-

tions; the vertical portion being of a greater thickness than the horizontal portion, and having one or more cavities in its vertical side
5 remote from the horizontal portion, and an angular, fluted, metallic plate embedded in the horizontal and vertical portions.

4. As an improved article of manufacture, a combined curb and gutter block comprising a horizontal portion, and a vertical portion, integral with the horizontal portion, and having one or more cavities in its vertical side
10

remote from the horizontal portion, and an angular, metallic reinforcement embedded in the horizontal and vertical portions.

In testimony whereof I have hereunto set my hand in presence of two subscribing witnesses.

WILLIAM H. FERGUSON.
